Primary Examiner—Stacia Cadmus(74) *Attorney, Agent, or Firm*—Klauber & Jackson LLC(57) **CLAIM**

The ornamental design for tire stud, as shown.

DESCRIPTION

FIG. 1 is a top front perspective view of the top of a tire stud of our new design, with the remainder of the body of said tire stud excluded by dotted lines;

FIG. 2 is a side elevational view of the design of FIG. 1;

FIG. 3 is a top view thereof; and,

FIG. 4 is an upper perspective view thereof, similar to FIG. 1, enlarged to better depict the said top of the tire stud, and with the remainder of the body depicted fragmentarily and schematically.
